UNITED STATES PATENT OFFICE.

LORA G. PRICE, OF LOS ANGELES, CALIFORNIA.

CASH BOX.

Application filed October 14, 1920. Serial No. 416,807.

To all whom it may concern:

Be it known that I, LORA G. PRICE, a citizen of the United States, residing at Los Angeles, in the county of Los Angeles and State of California, have invented new and useful Improvements in Cash Boxes, of which the following is a specification.

It is the object of the invention to provide a cash box which when opened will afford 10 convenient trays for holding coins of various denominations as well as bills of various denominations. The cash box, when closed, may be locked and thus afford convenient and safe means for carrying the cash contained therein.

The invention will be readily understood from the following description of the accompanying drawings, in which;

Figure 1 is a perspective view of the box 20 in its closed, locked position.

Fig. 2 is a plan view of the box in open position ready to be employed for making change.

Fig. 3 is a transverse section on the line 25 3—3 of Fig. 1.

The box, preferably, comprises a rectangular receptacle having the bottom 1 and the cover 2. The bottom is arranged as a tray, the base of which is provided with the 30 grooves 3 extending from the front to the rear walls of the bottom. These grooves are substantially semicircular and are of different sizes so that coins of various denominations may be received upon their edges 35 within the respective grooves. The various size grooves extend to various depths within the base so that the coins of various sizes received therein will be positioned with their upper edges substantially in alinement with the top of the bottom 1. The grooves 3 may be divided midway of their lengths by cross partition 4, each of the grooves thus formed being arranged to contain a certain number 40 of the coins of the various denominations.

45 The portions of the base between the various grooves forming the strips 5 are, preferably, graduated along their edges as shown at 6. These graduations are positioned proportional to the thickness of the 50 coins adapted to be received in the respective grooves so that the graduations will afford ready means for counting the number of coins in a groove. The coins are, preferably, stacked in the grooves in front of partition 4 from the front edge 7 of bottom 1 55 toward the partition 4; and the coins in the

grooves in rear of this partition are, preferably, stacked rearwardly from the partition. The graduations 6 may be numbered as shown at 8 in accordance with such a stacking arrangement in order to readily denote the number of coins in any groove.

60 The cover 2 comprises a tray with the top of the cover forming the base of the tray. This tray is divided transversely by the partition 9 in order to form the elongated receptacles 10 adapted to contain bills. Spring clips 11 may be provided in the respective receptacles 10 in order to yieldably hold stacks of bills in the receptacles. These 65 spring clips are, preferably, arranged at one end of the receptacles, and at one side of their opposite ends the receptacles may be provided with lips 12. These lips extend from the walls forming the cover and from 70 the partition 9 at the upper edges of the respective receptacles so as to afford means for holding one side of the ends of the bills within their receptacles. It will thus be seen that the opposite sides of the ends of the 75 bills are loose so that they may be readily grasped for withdrawing the bills.

78 The cover 2 is hinged to the bottom 1 as by the hinges 13 so that the cover may be swung downwardly over the bottom 1 as 85 shown in Fig. 1, in order to form a closed receptacle, or may be swung rearwardly from the bottom as shown in Fig. 2 in order that the coin tray and the bill tray will be conveniently positioned for use.

90 In order to prevent the coins falling from their grooves when the box is closed, a cover 15 fits within the open edge of the cover tray and is, preferably, hinged at its rear edge to the cover tray as shown at 16. The 95 edges of the coins being flush with the top of the bottom tray when the cover of the box is closed, the cover 15 will rest against the edges of the coins and will thus prevent movement of the coins in their grooves. The cover 15 may be provided with a finger aperture 17 at its swinging edge in order that it may be readily swung from one side to the other to obtain access to either the bill tray or the coin tray when the cash box is open 100 for use. A lock 18 may be provided for the box when in its closed position.

105 It will be noted that the construction as thus set forth, provides a convenient container for both bills and coins which, when 110 closed, will form safe means for carrying the contents of the box and which when open

will position the coin and bill trays convenient for use in making change.

The improved cash box will also be found especially convenient when checking the contents of a box; since a ready means is provided for carrying the money to a central office so that a teller may count the coins by simply reading the graduations upon the coin grooves.

10. Various changes may be made without departing from the spirit of the invention as claimed.

What is claimed is:

1. A cash box comprising a body, a coin tray in the body formed with grooves at various depths and of substantially semicircular form in cross section, a cover hingedly supported on the body, bill retaining means

within the cover, and a cover plate hingedly supported upon the cover and arranged between the cover and the body so that when the former is in closed position the plate will engage the coins contained in the grooves and prevent movement of the latter within the grooves.

2. A cash box comprising a body, a coin tray within the body, a cover hingedly supported on the body, bill retaining clips and lips within the cover, and a cover partition hingedly supported on the cover and adapted to overlie said tray when the cover is in closed position.

In testimony whereof I have signed my name to this specification.

LORA G. PRICE.
